UNITED STATES PATENT OFFICE.

MARTIN L. BOWDEN, JR., OF BROOKLYN, NEW YORK, ASSIGNOR TO J. B. BOWDEN & CO., OF NEW YORK, N. Y., A COPARTNERSHIP COMPOSED OF MARTIN L. BOWDEN, MARTIN L. BOWDEN, JR., AND GARDNER S. BOWDEN.

DESIGN FOR A RING.

Application filed February 17, 1923. Serial No. 5,189. Term of patent 3½ years.

To all whom it may concern:

Be it known that I, MARTIN L. BOWDEN, Jr., a citizen of the United States, and resident of the borough of Brooklyn, in the city and State of New York, have invented a new, original, and ornamental Design for a Ring, of which the following is a specification, reference being had to the accompanying drawing, forming part thereof.

The drawing shows a perspective view of a finger ring embodying my new design.

I claim:

The ornamental design for a ring substantially as shown.

MARTIN L. BOWDEN, JR.
